(57) **CLAIM**

The ornamental design for a top sheet of an absorbent pad, as shown and described.

DESCRIPTION

FIG. 1 is a view of a top sheet of an absorbent pad showing our new design; and,

FIG. 2 is another embodiment showing a longer view of the pattern that is shown on the top sheet of an absorbent pad in FIG. 1.

The broken lines in FIG. 1 and FIG. 2 are for environmental purposes only and do not form any part of the claimed design. The embossing (the seven stripes in the center of the design) is shown in FIG. 1 and FIG. 2 in hashed form to represent a distinction between the printing and the embossing, and the embossing forms part of the claimed design of FIG. 1 and FIG. 2.
